(57) **CLAIM**

The ornamental design for a clock, as shown and described.

DESCRIPTION

FIG. 1 is a perspective view of one embodiment of the clock.

FIG. 2 is a front view of the clock.

FIG. 3 is a back view of the clock.

FIG. 4 is a side view of the clock.

FIG. 5 is a side view of the clock.

FIG. 6 is a top view of the clock; and,

FIG. 7 is a bottom view of the clock.

The broken line showing of portions of the clock is for illustrative purposes only and forms no part of the claimed design.
